UNITED STATES PATENT OFFICE.

EDWARD WITTCOFF, OF ST. LOUIS, MISSOURI, ASSIGNOR TO SUPERIOR HAT COMPANY, OF ST. LOUIS, MISSOURI, A CORPORATION OF MISSOURI.

DESIGN FOR A HARVEST HAT.

Application filed June 13, 1928. Serial No. 27,109. Term of patent 14 years.

To all whom it may concern:

Be it known that I, EDWARD WITTCOFF, a citizen of the United States, residing in the city of St. Louis, State of Missouri, have invented a certain new, original, and ornamental Design for Harvest Hats, of which the following is a specification, reference being had to the accompanying drawing, forming a part thereof.

My new design comprises, a configuration, through impressions, openings, and embossments, in and upon the crown of a harvest hat, in resemblance of an owl's face, and, in the drawing, Figure 1 is a front perspective view and Figure 2 is a side perspective view of a harvest hat embodying my new design.

I claim:

The ornamental design for a harvest hat, substantially as shown and described.

EDWARD WITTCOFF.
